UNITED STATES PATENT OFFICE.

OTTO A. FREDERICKSON, OF WETHERSFIELD, CONNECTICUT, ASSIGNOR TO THE AMERICAN WIREMOLD COMPANY, OF HARTFORD, CONNECTICUT, A CORPORATION OF CONNECTICUT.

BRAIDING MACHINE.

Application filed April 18, 1925. Serial No. 24,201.

To all whom it may concern:

Be it known that I, Otto A. FREDERICKSON, a citizen of the United States, residing at Wethersfield, county of Hartford, and 5 State of Connecticut, have invented an Improvement in Braiding Machines, of which the following description, in connection with the accompanying drawings, is a specification, like characters on the drawings representing like parts.

This invention relates to braiding machines and more particularly to braiding machines of that type comprising a series of inner and a series of outer yarn carriers 15 which are moved in concentric circular paths in opposite directions.

In braiding machines of this type as now generally constructed, the inner and outer yarn carriers are supported from and rotated in opposite directions in concentric circles about a fixed tubular shaft. The yarn from the inner and outer yarn carriers leads inwardly towards the braiding point and the yarn from the outer carriers is alternately raised and lowered relatively to the inner carriers so that the inner carriers will pass alternately over and under the outer yarn as the carriers pass each other to produce the braided effect.

30 An urgent demand has recently arisen for braiding machines of this general type wherein the number of inner and outer yarn carriers may be greatly increased and the machine run at high speed. To increase the 35 number of yarn carriers in this type of braiding machines requires that the diameter of such machines be increased, that is, the diameter of the outer revolving drum which supports the outer yarn carriers, and 40 in part also supports the inner yarn carriers, must be increased, and since such increase in the diameter of the outer revolving drum removes the supporting portions of said drum further and further from the 45 central tubular shaft, the leverage and weight of the parts places a limit on this line of development. Not only is it necessary to increase the diameter of the outer revolving drum to increase the number of 50 the yarn carriers, but the raceway for the inner yarn carriers must be carried radially outward from the tubular shaft from which they have been supported, with the result that the parts sag under the increased

weight and leverage conditions and difficulty 55 is experienced in starting and stopping the machines quickly, and under high speed such structure chatters to such an extent as to be impracticable.

One of the objects of the present invention is to provide a machine of this general type wherein the outer revolving drum is associated with a fixed central drum which is itself coordinately enlarged with the outer revolving drum, so that the objectionable 60 leverage effect incident to the enlargement 65 of the outer revolving drum of the old structure, as hereinbefore briefly pointed out, may be entirely eliminated and smooth practical running of the parts is effected. 70

In accordance with the present invention, the relation between the upstanding walls of the outer revolving and inner or centrally fixed drum may be maintained without increasing the leverage effect between the two, 75 regardless of the size of the machine, with the result that any number of inner and outer yarn carriers may be provided in such machine without the introduction of the chattering and impractical operative conditions incident to increasing the leverage effect from the central tubular shaft in the old form of the machine.

The relation between the outer revolving drum and the central fixed drum in the present invention is such that a raceway is 85 formed for the inner yarn carriers between the upstanding walls of the outer revolving and central fixed drum which may be of a width substantially equal to the radial dimensions of the inner carriers, and since the radial extent of the outer revolving drum from the inner fixed drum, or the distance between the upstanding walls of the two drums, has not been increased in providing 90 accommodations for a greater number of inner yarn carriers, it follows that a braiding machine constructed in accordance with the present invention is adapted for the employment of any number of inner and outer 95 yarn carriers, as will more fully appear. 100

In braiding machines of this general type, it is not unusual to place the braided covering about a core, and prior to the laying of the braided covering upon the core, to place 105 upon the uncovered core a size, or it may be, tape or other wrapping material, and in accordance with the present invention, the

central fixed drum provides for the support of the core-treating elements within the bore or hollow portion of the fixed drum.

It is now the common practice in machines of this general class to superimpose two or more complete sets of braiding elements or machines, in order to lay upon the core two or more layers of the braid. When, however, such superimposed conditions have been attempted in the old type of such machines, difficulty has been experienced in securing access to the upper one of such braiding elements, and another feature of the present invention, therefore, consists in so relating the parts of the braiding machine that the vertical height thereof shall be minimized to enable the machine attendant to have convenient access to any one of the series of superimposed braiding elements.

20 The invention and novel features and new combination of parts will best be made clear from the following specification and accompanying drawings of one good form of the invention.

25 In the drawings:—

Fig. 1 is a transverse section of a braiding machine containing the present invention;

Fig. 2 is a top plan view with parts in section on the line 2—2 of Fig. 1; and

30 Fig. 3 is a transverse section similar to that of Fig. 1, with some of the parts omitted, showing a braiding machine of the present invention as having been constructed for the accommodation of an increased number 35 of inner and outer yarn carriers, as compared with the machine of Fig. 1, and showing also certain modifications of parts.

The machine frame for supporting the braiding elements may be of any usual or 40 desired character suitable for this purpose and as shown comprises a series of upstanding supports 1, of which there may be any suitable number. Mounted upon the supports 1 are the outstanding flange portions 45 2 of arms 3 which form a convenient means for supporting the central fixed drum. In the present instance of the invention, the arms 3 are formed integral with the central fixed drum 4, and while this is found 50 to be a convenient and practical construction, the supporting arms 3 may be otherwise connected to the fixed central drum.

Supported from the central fixed drum 4 is the outer revolving drum 5 between the 55 upstanding wall of which and the upstanding wall of the central fixed drum 4 a raceway is provided for the inner yarn carriers, and such raceway may be substantially equal in width to the length or radial dimensions 60 of the inner yarn carriers.

In the present instance of the invention, the central fixed drum 4 is provided with a shoulder portion 6 for the support of an intermediate drum 7. Between the shoulder portion 6 of the central fixed drum and the

outstanding flange 8 of the intermediate drum is an anti-friction bearing, preferably formed by a series of balls 9 contained in suitable circular raceways formed in the shoulder 6 and outstanding flange 8.

70 Below the ball raceway the central fixed drum is provided with the circular bearing 10 which fits in the adjacent surface of the intermediate drum 7, as indicated in Fig. 1, and serves to steady the drum 7 during its 75 rotary movement, as will later appear.

The lower portion of the intermediate drum 7 is outturned as at 11, and such outturned portion 11 is provided with an upstanding flange 12 having a ball raceway 13 for the reception of a series of anti-friction balls 14 interposed between the intermediate drum 7 and the outwardly extending portion of the outer revolving drum 5, as indicated in Fig. 1.

80 Mounted in suitable bearings on the machine frame is the driving shaft 15 which may be driven from any suitable source of power through the belt pulley 16 or other means.

90 The drive shaft 15 carries clutch members 17, shown by dotted lines in Fig. 1, through which may be driven the gear 18 which meshes with a circular rack 19 on the intermediate drum 7 and a similar circular rack 20 secured to the outer revolving drum 5, the construction being such that when the clutch members 17 are in operative engagement, the beveled gear 18 will be rotated, thereby turning the intermediate drum 7 and the outer revolving drum 5 in 100 opposite directions. The details of the clutch mechanism and the electric stop 21 form no essential part of the present invention, and since such parts are now old and well-known in the art, a description thereof is unnecessary.

95 Secured to the intermediate drum 7 is a driver disk 22 which may be conveniently associated with the intermediate drum 7 by a key 23. The driver disk 22 carries means 110 for traversing the inner yarn carriers in their raceway or circular path, as will presently appear.

115 Mounted upon the driver disk 22 are a series of shafts 24 mounted in suitable bearings 25 carried by the driver disk, and each shaft is provided with a beveled pinion 27 which engages with the teeth of a fixed disk or spider frame 28 which is secured to the central fixed drum 4 as by means of the key 29. Each of the shafts 24 carries a driving roll 30 adapted to engage a driving wheel 31 mounted on the inner yarn carriers 32.

120 Between the upstanding wall 5 of the outer revolving drum and the upstanding wall of the inner fixed drum 4 a raceway is provided for the inner yarn carriers 32. As indicated in Fig. 1, each inner carrier 32 has a shoe 33 which travels in a recess 34 formed in the upstanding wall of the outer 130

revolving drum. The inner carriers 32 extend from their respective shoes 33 inwardly and at their inner ends each has a roller 35 adapted to support the inner end of each 5 inner carrier. As indicated in Fig. 1, the supporting rollers 35 rest upon the hub portion 36 of the spider frame 28, and slightly inward of the supporting roller 35 is the yarn guiding disk 37 for each of the inner 10 yarn carriers, the construction being such that upon operation of the main or driving shaft 15, the intermediate drum 7 will be rotated to thereby actuate the driver disk 22 and through the driver rolls 30 traverse 15 the inner yarn carriers in their circular raceway between the upstanding wall of the outer revolving drum 5 and the upstanding wall of the inner fixed drum 4. The width of the raceway which thus accommodates 20 the inner yarn carriers is substantially the same as the radial dimension of the inner yarn carriers, and such relation of parts is maintained regardless of the size of the outer revolving drum and the inner fixed 25 drum. From this relation of parts it will be apparent that the raceway for the inner yarn carriers may be of any length and consequently provided for the accommodation of any desired number of inner yarn 30 carriers without at the same time objectionally increasing the radial distance between the upstanding wall of the outer revolving drum and the upstanding wall of the inner fixed drum.

35 As hereinbefore shown, the outer revolving drum 5 has a vertical bearing wall 38 which is shown as resting upon the outer adjacent wall of the intermediate drum 7, and this construction may sometimes be desirable in order to effectively and more positively associate the intermediate and outer revolving drums. This bearing between the two, however, is not always necessary, because the roller raceway between the outer 45 revolving drum and the intermediate drum may suffice to hold the parts in their desired running relation horizontally, while the ring 39 between the driver disk 22 and the hub portion of the outer revolving drum 50 serves to maintain the outer revolving drum seated upon its ball raceway.

The upstanding wall of the outer revolving drum 5 has secured thereto an outer 55 yarn carrier support 40 to which may be secured a series of brackets 41, for supporting the outer yarn carriers 42. In the present instance, the brackets 41 have lugs 43 for supporting the bearings 44 of the outer yarn carriers 42, and between the said 60 brackets 41 of each yarn carrier there is a guide 45 in the form of a bridge bar connecting the brackets 41, and the guide is provided near its ends with stops 46 for limiting the travel of the yarn as it is drawn 65 from the outer yarn carriers. In some cases

it may be desirable to have the outer yarn carriers held from overrunning by means of a brake, such as 47, which may have a resilient bearing against the body of the yarn, as indicated in Fig. 1.

70 It will not be necessary herein to further detail the specific construction of the inner yarn carriers since they may be of the general type shown, or otherwise constructed; it will be sufficient to note that as the inner 75 yarn carriers and outer yarn carriers are moved in opposite directions in their circular paths of travel, the yarn *a* from the outer yarn carriers is caused to alternately move above and below the inner yarn carriers as they traverse in their circular path, 80 as is usual in this type of machine. One of the arms for raising and lowering the outer yarn as described is indicated at 48, Fig. 1. Such arm 48 may be conveniently actuated 85 by a cam 49 formed in the fixed ring 50 rising from the machine frame.

From the construction thus far described it will be apparent that a raceway is formed 90 between the upstanding walls of the outer revolving drum 5 and the inner fixed drum 4 which is of a width, regardless of its length, equal to or substantially equal to the radial dimension of the inner yarn carriers, and when the outer revolving drum is enlarged in diameter to accommodate an increased number of the inner yarn carriers, 95 the central fixed drum 4 is coordinately enlarged, so that the general characteristics of the raceway hereinbefore described as 100 formed between the upstanding wall of the outer revolving drum and the upstanding wall of the central fixed drum are maintained.

105 It will also be apparent that the radial extent of the outer revolving drum from its bearing relation with the central fixed drum is not materially altered or changed when the outer revolving drum and central fixed drum are themselves coordinately enlarged to provide for an increased number 110 of the inner yarn carriers, so that the weight of the outer and inner yarn carriers which is transmitted wholly or partially through the outer revolving drum to the central fixed 115 drum, acts through a leverage which has not been materially increased, even though the capacity of the machine itself for the accommodation of an increased number of inner and outer yarn carriers has been increased.

120 By the disposition of the associated parts, and particularly the inner fixed drum 4, the intermediate drum 7 and the outer revolving drum 5, in connection with the bearings between these parts, and especially the two horizontal ball raceways, the revolving drums and associated elements forming a 125 complete machine operate in a space of minimum height, with the result that when an- 130

other machine of like structure is superimposed, the parts of the upper machine are readily accessible to the machine attendant standing upon the floor.

5 In the illustrated embodiment of the invention, the inner and outer yarns, which may be of any usual kind of filament, such, for instance, as cotton, wool, silk or wire, are brought together at the braiding point 10 51 which may be located at the lower end of a tube 52 supported by a collar or ring 53 which itself may be supported from a convenient stationary part. The braiding point 51 in the present illustration is shown 15 disposed axially above the central fixed drum 4, and upwardly through the drum 4 extends the core 54 which is to be covered. It is sometimes desirable to place upon the core a preliminary covering, such, for instance, as tape, paper or other insulated or water-proof material, and in accordance 20 with the present invention, the central fixed drum 4 may have mounted therein such preliminary core treating devices.

25 As indicated in Fig. 1, the central fixed drum 4 has an inwardly extending flange 55 on which is mounted a ring 56 having brackets 57 for the support of the tape or paper strip or other material, as indicated 30 at 58. The ring 56 has its outer periphery provided with teeth 59 which engage with the teeth of the pinion 60 mounted upon the vertically extending shaft 61 which may be 35 driven from any suitable source of power and which, in the present instance, is provided with the beveled gear 62 at its lower portion, which meshes with a pinion 63 mounted on a shaft 64 driven from some going part. From the construction of the 40 elements within the central fixed drum 4 it will be apparent that as the ring 56 is rotated and the braiding machine is operated, that the core will be moved endwise by suitable feeding means not herein shown, 45 and as the core is fed upwardly, in the present instance, the tape or paper strip or strips 58 will be laid spirally around the core before the core is covered by the braiding filaments at the braiding point. If desired, the core may be passed through a 50 suitable composition tank, which composition may be substituted or used in addition to the preliminary wrapping devices, and conveniently located in the hollow of the central fixed drum.

55 As hereinbefore stated, when it is desired to increase the number of yarn carriers that may be employed in a machine constructed in accordance with the present invention, the outer revolving drum and the central fixed drum are coordinately enlarged, substantially as indicated in Fig. 3, so that while the machine is rendered capable of 60 accommodating a larger number of yarn carriers, the radial distance between the up-

standing walls of the outer revolving drum and of the central fixed drum may remain substantially unchanged, and provide between such upstanding walls of the two drums a raceway for the inner yarn carriers without the introduction of increased leverage. 70

75 Referring to Fig. 3, the raceway for the inner yarn carriers is shown as formed between the upstanding walls of the outer revolving drum and the upper edge portion of the central fixed drum 4. In other words, in Fig. 3, the inner supporting rollers 35 of the inner yarn carriers 32 travel upon the upper inclined surface 65 of the central 80 fixed drum 4. In this construction also the spider rack 28 has its upper portion cut away as at 66 to permit the free passage of the yarn between the guide 37 at the inner end of each carrier and the parts beneath. 85

90 With the exception that in Fig. 3 the outer revolving drum and the central fixed drum have been made of larger diameter than indicated in Fig. 1, to provide for an increased 95 number of inner yarn carriers, and the inner supports for the inner yarn carriers rest upon the upper end portion of the central fixed drum, the parts are substantially the same as in Fig. 1. 95

What is claimed is:

1. In a braiding machine, the combination of an outer revolving drum having outer yarn carrier supports, a fixed central drum extending upwardly through the outer revolving drum and having its axial opening adapted to contain means for applying a strip of covering material upon the core to be braided, inner yarn carriers, a raceway for the inner yarn carriers formed between the vertical walls of the fixed central and outer revolving drums, and means for moving the outer drum and inner yarn carriers in circular paths in opposite directions. 100

105 2. In a braiding machine, the combination of an outer revolving drum having outer yarn carrier supports, a series of inner yarn carriers having a race-way, a fixed central drum about which the outer revolving drum rotates and having a central well and an annular wall that is spaced inwardly from the outer revolving drum only to a sufficient extent to provide a race-way for the inner carriers between the two drums, and means 110 for traveling the outer yarn carriers and inner yarn carriers in circular paths in opposite directions. 115

120 3. In a braiding machine, the combination of an outer revolving drum having outer yarn carrier supports, a series of inner yarn carriers having a race-way, a fixed central drum about which the outer revolving drum rotates and having a central well and an annular wall that is spaced inwardly from the outer revolving drum only to a sufficient 125 130

extent to provide a race-way for the inner carriers between the two drums, a bearing for the outer revolving drum which lies radially outward beyond the inner limit of 5 the circular race-way, and means for traveling the outer yarn carriers and inner yarn carriers in circular paths in opposite directions.

4. In a braiding machine of the character described, the combination of an outer revolving drum having outer yarn carrier supports, a fixed central drum having a race-way between it and the outer revolving drum, said fixed central drum having a large 10 central well and an annular wall that is spaced inwardly from the outer revolving drum only to a sufficient extent to provide the race-way for the inner yarn carriers between the drums, a series of inner yarn carriers, and means for traveling the inner yarn carriers in a circular path about the race-way, whereby the distance between the fixed and revolving drum remains constant regardless of the size of the braiding machine 15 and affords a construction of minimum weight.

5. In a braiding machine of the character described, the combination of an outer revolving drum, a fixed central drum about 20 which the outer drum rotates and having a central well, the vertical walls of the two drums being radially separated only to an extent sufficient to provide a raceway passage for inner yarn carriers that the size of 25 the machine may be indefinitely increased to accommodate an increased number of inner yarn carriers without increasing the distance between the vertical walls of the fixed and revolving drums, a series of inner yarn carriers having horizontal axes, and means for 30 traveling the inner yarn carriers in a circular path in said raceway.

6. In a braiding machine of the character described, the combination of an outer revolving drum, a fixed central drum about 35 which the outer drum rotates and having a central well, the vertical walls of the two drums being radially separated only to an extent sufficient to provide a raceway passage for inner yarn carriers that the size of 40 the machine may be indefinitely increased to accommodate an increased number of inner yarn carriers without increasing the distance between the vertical walls of the fixed and revolving drums, a series of inner yarn carriers having horizontal axes and supported 45 at their inner and outer ends by the two drums, and means for traveling the inner yarn carriers in a circular path in said race-way.

7. In a braiding machine, the combination of an outer revolving drum for outer yarn carriers, a fixed central drum that rotatably 50 supports the outer revolving drum, the cylindrical walls of which drums define the

width of the raceway for inner yarn carriers that the size of the two drums may be coincidentally increased to provide for an increase in the number of inner yarn carriers while maintaining the same radial separation of 70 the vertical walls of the drums, a series of inner yarn carriers, and means for traveling the inner and outer yarn carriers in opposite directions.

8. In a braiding machine, the combination of a central fixed drum, an intermediate drum, and an outer revolving drum for outer yarn carriers, a circular ball bearing between the central fixed drum and intermediate drum, and a circular ball bearing 75 between the outer revolving drum and intermediate drum disposed horizontally beyond the ball bearing between the central and intermediate drums.

9. In a braiding machine, the combination of an outer revolving drum having outer yarn carrier supports, a fixed central drum extending through the outer revolving drum and forming a raceway for inner yarn carriers between the vertical walls of said 80 fixed and revolving drums of a width substantially equal to the radial dimension of the inner yarn carriers, means within the central fixed drum for laying a preliminary covering upon the core, and means for 85 traveling the outer and inner yarn carriers in circular paths in opposite directions.

10. In a braiding machine, the combination of an outer revolving drum for outer yarn carriers, a fixed central drum, the cylindrical walls of which drums define the width of the raceway for inner yarn carriers that the size of the two drums may be coincidentally increased to provide for an increase in the number of inner yarn carriers while maintaining the same radial separation of the vertical walls of the drums, means within the central fixed drum for applying an unbraided preliminary covering 90 upon the core, a series of inner yarn carriers, and means for traveling the inner and outer yarn carriers in opposite directions.

11. In a braiding machine, the combination of a central fixed drum of large diameter, an intermediate drum that encircles the fixed drum, a revolving outer drum having a raceway for inner yarn carriers and having a hub that rotates about the intermediate drum, a driver for the inner carriers mounted on the intermediate drum, and means for rotating the intermediate drum about the fixed drum to advance the inner carriers in their path of travel.

12. In a braiding machine, the combination of a central fixed drum of large diameter having an outwardly projecting shoulder, an intermediate drum having an inwardly projecting portion above the shoulder, a series of anti-friction balls be- 125

tween the projection and shoulder, a second projection radially distant from the first projection extending from the intermediate drum, an outer revolving drum, and a series 5 of anti-friction balls on said second projection supporting the outer revolving drum.

13. In a braiding machine, the combination of a central fixed drum of large diameter, a rotating member inside the drum 10 and carrying covering material for the core, means for rotating the member within the drum, an outer revolving drum supporting outer yarn carriers, a series of inner yarn carriers, and means for traversing the inner 15 and outer yarn carriers in opposite directions to braid filaments upon a covered core.

14. In a braiding machine, the combination of an outer revolving drum provided with supports for the outer yarn masses, a 20 series of inner yarn carriers having a race-way, a fixed central drum about which the outer revolving drum rotates and having a central well the diameter of which is many times greater than the diameter of the braid 25 formed upon the machine, said fixed drum having an annular wall that is spaced inwardly from the outer revolving drum only

to a sufficient extent to provide a race-way for the inner carriers between the two drums, and means for advancing the outer 30 and inner yarn carriers in circular paths about the axis of the braiding machine.

15. In a braiding machine, the combination of an outer revolving drum provided with supports for the outer yarn masses and 35 having a sufficiently large circumference to form the race-way for the outer ends of a large number of inner yarn carriers, a series of inner yarn carriers engaging said race-way and having a radial length much 40 less than the radius of said drum, a fixed central drum provided with a race-way for the inner ends of the inner yarn carriers and having a large central well and an annular wall that is spaced inwardly from the outer 45 revolving drum only to a sufficient extent to accommodate the radial length of the inner carrier between the two drums, and means for advancing the outer and inner yarn carriers in circular paths in opposite directions.

In testimony whereof, I have signed my name to this specification.

OTTO A. FREDERICKSON.
